H. T. LIBBY

HYDRAULIC CONVEYER

Filed May 13, 1922

UNITED STATES PATENT OFFICE.

HARRY T. LIBBY, OF KANKAKEE, ILLINOIS.

HYDRAULIC CONVEYER.

Application filed May 13, 1922. Serial No. 560,580.

To all whom it may concern:

Be it known that I, HARRY T. LIBBY, a citizen of the United States, residing at Kankakee, in the county of Kankakee and 5 State of Illinois, have invented a certain new and useful Improvement in Hydraulic Conveyers, of which the following is a specification.

This invention relates to hydraulic conveyers of use wherever dirt or other waste material can be conveniently transported by the aid of water under pressure. The invention is specially applicable to use in connection with stone quarries, gravel pits and 15 the like where piles or layers of dirt material, with or without the presence of rock in comparatively small sized pieces, has to be removed so that the workmen can get at the solid rock or other material which 20 is to be quarried. Because of this use of the device, it is shown in the drawings as installed at the edge of a stone quarry; but this illustration of the invention is not intended to in any way limit its scope or usefulness.

The object of the invention is to provide an apparatus which can be very easily and cheaply made, which is very efficient in use, which is not readily liable to get out of 30 order, which is adapted for ready transportation with very slight labor from one point to another for work and from one point to another in the work, the same being adapted to wash away the dirt or other material to be conveyed away, and to thence 35 convey that material to a distant point where it is out of the way of the workmen who are to quarry or otherwise remove the material which is in the first instance 40 covered by the waste material. The invention consists in means for carrying out the foregoing and other objects, which has in addition the special advantage of being 45 capable to transport the material to be carried from a lower to a higher level and to 50 do this efficiently and cheaply without the installation of expensive machinery. The invention further consists in many features and details of construction which will be 55 hereafter more fully set forth in the specification and claims.

Referring to the drawings in which like numerals designate the same parts throughout the several views: Figure 1 is a side 60 view largely in section of one edge of a stone quarry in which the mechanism of

this invention is just beginning its work at a given point; Figure 2 shows the same territory with the work approximately completed at that particular point; and Figure 3 is a longitudinal sectional view through the injector end of the conveyer pipe which forms the most vital part of the invention.

Figures 1 and 2 show a bed of rock 10, which is to be quarried, the same covered with a layer of more or less ordinary dirt 12, which is to be removed, this dirt having piled upon it at the edge 14 of the quarry a ridge or pile 16 of dirt and rock composed of ordinary dirt and 65 chunks of rock 18, usually placed there by steam shovel operations in the quarry. The work in hand is to remove the pile of dirt 16 and the layer of dirt 12 a substantial 70 distance to the right of the figures here shown, so that workmen may remove the pieces of rock 18 and may quarry the solid rock 10, and to do this with the simple apparatus, efficient in operation and satisfactory in use.

The particular embodiment of the invention shown in the drawings includes conventional form of washing nozzle mechanism 20, having a tiltable nozzle 22, adapted to direct a stream of water 24 in any desired direction for the purpose of driving dirt before it. This mechanism 20 is supplied with water under pressure through a system of piping 26-28 of any conventional form. In the particular case here 80 illustrated, the water under pressure is delivered to pipe 28 from centrifugal pump 30, driven by any suitable means, as, for instance, an electric motor 32, the pump drawing water into itself through a pipe 34, leading to any suitable source of supply, not shown.

Pipes 26 and 28 are joined together by a T junction 36, to whose branch 38 is attached a hose 40, leading to the side of pipe 100 26-28 and terminating in a nozzle 42 supported by a screen cap 44, having in it perforations of sufficient size so that water, dirt and rock particles of normal size, which it is desired to carry away, may pass 105 through them. This cap 44 is suitably attached, for instance by screw threads 46 on the end of a waste material conveyer pipe 48 leading away to a distant point at the right of the figures shown to the place of disposal of the material to be conveyed. While pipe 48 has been referred to as a 110

single pipe, there is nothing in the invention to prevent its being a line of pipe of considerable length, made up of separate pieces of pipe. The discharge end 42^a of 5 nozzle 42 enters the left hand intake end of pipe 48 a sufficient distance so that when water from pump 30 is forced through this nozzle 42 in a stream 50 inside of pipe 48, the device acts as an injector sucking any 10 and all materials which will pass through the screen 44 into the pipe 48 in the general directions of the arrows shown in Figure 3. The material so entering the screen, in passing from the screen to the end 42^a 15 of the nozzle, travels under a vacuum suction created by the stream 50. As soon as the material passes the end 42^a, it mingles with the stream and is thereafter carried by hydraulic pressure to the right through the 20 pipe 48.

The injector is made of sufficient power, using the principles well understood in the injector art, so that when the screen 44 is introduced in a puddle or pool 52 of water 25 and other material below the general level of the dirt 12, or in any other position below the level of the end of pipe 48, that material carried into the pipe 48 by the injector will be forced clear through the pipe and delivered from its right hand end, notwithstanding 30 this elevation of the delivery end of the pipe 48.

In the operation of the device as applied to the particular stone quarry here shown, 25 the mechanism is first installed in the general position of Figure 1, thereupon the pump 30 is started, valves 54 and 56 controlling the pipes in which they are located are opened and the water is allowed to travel 40 through pipe 26 to nozzle 22 and through pipe 40 to nozzle 42. The stream of water 24, delivered by nozzle 22, is manually directed to wash down dirt from pile 16 and from layer of dirt 12 into the depression 52 45 adjacent to the screen 44—the water, of course, in seeking its lowest level also entering the pool 52 and covering the screen 44. With the various parts and materials in this 50 position, the rapid passage of water through nozzle 42 to form the stream 50 in pipe 48 sucks the water and dirt in pool 52 through the perforations of the screen 44 into the pipe 48 and finally delivers it from the discharge or right hand end of pipe 48. The 55 operator continues to manipulate nozzle 22 until a condition which is illustrated in Figure 2 is reached, in which practically all of the free dirt has been removed, leaving the upper surface of the rock 10 clear and clean 60 except for more or less large pieces of stone 18 which rest thereon and are afterwards manually removed, if it is found desirable.

During the operation described, the pipe 48 and the screen 44 connected with it may 65 be moved if desired to reach the lowest point

to which water will flow on top of the rock 10 and this may be done by ordinary workmen without special tools and without the necessity of laying foundations and making other permanent arrangements—which is 70 ordinarily necessary in installing material for pumping from a lower to a higher level.

The operator can, by manipulating the valve 56, control the amount of water delivered to nozzle 42 to thereby provide sufficient power to carry the material to be conveyed through pipe 48, regardless of the height to which it may be necessary to carry the discharge end of the pipe 48 in order to properly dispose of the waste material. In 80 other words, when the discharge end of pipe 48 is comparatively low as regards the nozzle 42, a comparatively low pressure of water may be delivered through nozzle 42 and this pressure may be increased by opening 85 valve 56 as the discharge end of pipe 48 is raised. The same result may, of course, be accomplished by initially installing different sized nozzles 42.

Having thus described my invention, what 90 I claim as new and desire to secure by Letters Patent is:

1. In apparatus of the class described a unitary equipment including in combination, a force pump, a dirt washing nozzle 95 driven by said pump and a screen protected injector actuated waste material carrier pipe also operated from said pump, there being flexible connections between the pump and said nozzle and said carrier whereby said 100 nozzle and said carrier may be moved a considerable distance away from each other.

2. In apparatus of the class described a unitary equipment including, in combination, a force pump, a dirt washing nozzle 105 driven by said pump and a screen protected injector actuated, waste material carrier pipe also operated from said pump, there being flexible connections between the pump and said nozzle and said carrier whereby 110 said nozzle and said carrier may be moved a considerable distance away from each other, and valves between the pump and said nozzle and between the pump and said conveyor for the purposes set forth. 115

3. A hydraulic conveyer comprising a dirt washing nozzle, a screen protected injector, a waste material carrier, a water pump, flexible water conveying pipes connecting said pump with said nozzle and with said carrier, a waste pipe in communication with said carrier, said pump being adapted to force water through said nozzle and through said carrier and into said last named pipe, the water flowing through said 120 carrier and into said last named pipe being adapted to suck dirt and small rock through said screen and to convey it away, through said last named pipe. 125

4. A hydraulic conveyer comprising a dirt 130

washing nozzle, a flexible hose in communication with said nozzle, a valve adapted to control the flow of water through said hose, a water pump, a water pipe connecting said pump with said valve, a second valve in communication with said water pipe, a flexible hose in communication with said second named valve, a screen secured to the free end of said second named hose, a waste pipe connected to the free end of said screen and a nozzle surrounded by said screen and being in communication with said second

named flexible hose, whereby a flow of water through said nozzle will create a partial vacuum in the space enclosed by said screen, 15 thus sucking dirt and small rock through the screen and into the path of the stream of water flowing from the end of said nozzle, whereupon the stream of water will continue to convey the dirt and rock through 20 said waste pipe.

In witness whereof, I have hereunto subscribed my name.

HARRY T. LIBBY.
